FIG. 2

FIG. IA

FIG. 1B

The dominant features of my design reside in the portions shown in full lines.

The drawings are stippled to indicate color contrast.

I claim:

The ornamental design for a game board, as shown and described.
